ELECTRONIC RECHARGEABLE FLASH ATTACH-
MENT FOR A PHOTOGRAPHIC CAMERA OR
SIMILAR ARTICLE

Martin S. Ackerman, East Hills Village, N.Y., assignor
to Perfect Film & Chemical Corporation, Manhasset,
N.Y., a corporation of Delaware

Filed June 7, 1967, Ser. No. 7,380

Term of patent 14 years

(Cl. D61—1)

FIG. 1   *FIG. 2*

FIG. 3   *FIG. 4*

FIG. 5

FIG. 6

FIG. 7

FIG. 1 is a front elevational view of an electronic rechargeable flash attachment for a photographic camera or similar article, showing my new design;

FIG. 2 is a rear elevational view;

FIG. 3 is a top plan view;

FIG. 4 is a bottom plan view;

FIG. 5 is a side view;

FIG. 6 is an opposite side elevational view; and,

FIG. 7 is a front, side and bottom perspective view thereof.

I claim:

The ornamental design for an electronic rechargeable flash attachment for a photographic camera or similar article, as shown and described.
